Don D. Myers, Toledo, Ohio, assignor to The
Blandon Manufacturing Company

Application March 31, 1932, Serial No. 602,280

31 Claims. (Cl. 311—82)

This invention relates generally to furniture and has particular reference to supporting legs for an article of furniture.

One of the primary objects of this invention 5 is to provide supporting legs of the above mentioned character which may be collapsed to inoperative positions when the article of furniture is not in use.

Further, the invention contemplates the provision of supporting legs of the above mentioned 10 character together with means operating upon movement of one of the supporting legs to collapsed position to effect a successive or sequential movement of the remaining legs to collapsed position.

Still further the invention contemplates the provision of resilient means which will tend to hold the legs in supporting or collapsed positions and which will also operate to move the actuating 20 connections between the several legs to locked positions.

This application is a continuation in part of my application Serial No. 532,447, filed April 24, 1931, and entitled "Table".

25 Numerous other objects and advantages of this invention will become more apparent as the following description proceeds, particularly when reference is had to the accompanying drawings, wherein:

30 Fig. 1 is a perspective view of a table in which the invention is incorporated, the view being taken looking downwardly on the table from one corner thereof;

Fig. 2 is a perspective view of the table shown 35 in Fig. 1 looking upwardly toward the under side of the table and from one side thereof;

Fig. 3 is a sectional view taken substantially on the line 3—3 of Fig. 2;

Fig. 4 is a sectional view taken substantially 40 at right angles to Fig. 3;

Fig. 5 is a sectional view taken substantially on the line 5—5 of Fig. 3;

Fig. 6 is a fragmentary bottom plan view of the table showing the legs in operative position;

45 Fig. 7 is a bottom plan view of the table showing the legs in collapsed position;

Fig. 8 is a perspective view showing the positions assumed by the legs during the collapsing thereof;

50 Fig. 9 is a view similar to Fig. 1 showing a slightly modified form of construction;

Fig. 10 is a fragmentary bottom plan view of the table shown in Fig. 9 showing the legs in open position;

55 Fig. 11 is a fragmentary perspective view show-

ing the positions assumed by the legs during the collapsing thereof;

Fig. 12 is a sectional view taken substantially on the line 12—12 of Fig. 10;

Fig. 13 is a detail perspective view of one of 5 the elements forming a part of the structure shown in Fig. 10;

Fig. 14 is a sectional view taken substantially on the line 14—14 of Fig. 12;

Fig. 15 is a sectional view taken substantially 10 on the line 15—15 of Fig. 12; and

Fig. 16 is a sectional view taken substantially 15 on the line 16—16 of Fig. 12.

As brought out above, the invention is directed more particularly to supporting legs for 15 an article of furniture and to means providing for the operation of all of the legs upon movement of one of the legs to open or collapsed positions. The invention will find utility when incorporated in any article of furniture, but for the purpose 20 of illustration, the invention will be described more particularly as being incorporated in a table construction.

Referring then particularly to the drawings 25 wherein like reference characters designate corresponding parts throughout all views, the numeral 20 designates generally an open frame which will, in the case of a table construction, preferably be substantially rectangular. This frame is provided with a downwardly depending 30 flange 21 within which the legs hereinafter to be described are adapted to fold, and the upwardly extending flange 22 within which the table top 23 is positioned. The table top is preferably supported at its edges on the horizontally extending 35 portion 24 of the frame 20 and is removably held in position by pivoted clips 25 which are carried by the under face of the table top and engage the under face of the horizontal portion 24 of the frame.

40 Disposed at the four corners of the frame 20 are supporting legs 30 and 31, the legs 30 being diagonally opposite each other and the legs 31 being at diagonally opposite corners. The legs 30 and 31 are not themselves directly connected 45 to the frame 20, these legs being indirectly hinged to the frame by braces rigid with the upper ends of the legs and extending normal thereto.

The structure of these braces or bars will be 50 better understood by reference to Figs. 2 to 4, inclusive, of the drawings wherein it will be noted that rigid with the legs 30 and projecting in a direction normal to these legs at the upper ends thereof are braces or bars 32. These braces 55

have their upper edges 33 parallel with the under face of the adjacent portion 24 of the frame and are hingedly connected to this frame by hinge plates 34. It will be noted that the braces 32 are so arranged that they extend along opposite sides of the table and thus form hinge connections for the legs 30 providing for the collapsing or folding of these legs in directions transverse to the planes of the braces.

10 Rigid with the legs 31 at the upper ends thereof and projecting normal to these legs are braces or bars 35. These bars have their upper edges parallel to and adjacent the corresponding portions 24 of the frame 20 and are hingedly connected to these portions of the frame by hinges 36 and 37. It will be noted that the braces 35 lie on opposite sides of the table frame and thus provide for the folding or collapsing of the legs 31 along the sides of the frame to which the braces 32 are secured.

15 Since stability and lightness are both desirable characteristics in a foldable table construction, the braces 32 and 35 are preferably of flaring skirt shape, as clearly indicated in Figs. 1, 3, and 25 4 of the drawings. Further, these braces are preferably of tapered cross sectional thickness, being of greater thickness adjacent their respective legs and being of less thickness at their free ends.

20 30 It will be noted that the braces 32 and 35 extend from their respective legs toward the next adjacent legs in the series. The braces 32, however, are longer than the braces 35, with the result that the free ends of the former braces 35 are closer to the legs 31 than the free ends of the braces 35 are to the legs 30. It will be noted further that the axes of the hinges 36 and 37 intersect the axes of the hinges 34 adjacent the inner corners of the several legs of the table.

25 40 The free end of each brace 32 is cut on an angle, and hingedly connected as by a hinge 40 to this free end is a plate 41. It will be noted that the axis of the hinge 40 bisects the angle between the adjacent axes passing through the 45 hinges 36 and 37 and the hinges 34. Each plate 41 is hingedly connected as by a hinge 42 to the adjacent portion of the adjacent leg 31. It will be noted, by reference to Fig. 6 of the drawings, that the hinge plate 41 is connected by offset 50 portions to the hinges 40 and 42 and that the axis of the hinge 40 is disposed slightly out of the plane of the axes of the hinge 42 and hinges 34.

55 Each brace 35 is provided on its free end with a plate-like extension 45 which is hingedly connected to the table frame to move with its respective brace by the hinge 37 and by a second hinge 46. Each plate 45 is provided with an angular end portion hingedly connected as by a hinge 47 to a plate 48, this latter plate being 60 similar to the plate 41. Each plate 48 is connected as by a hinge 49 to the adjacent leg 30.

65 It will be noted that the plate 48 is connected by offset portions to its respective hinges 47 and 49 in the same manner as is the plate 41. It will be noted further that the axis of the hinge 47 substantially bisects the angle between the adjacent axes of the hinges 36 and 37 and the 70 hinges 34. Still further, the axis of the hinge 47 is disposed slightly out of the plane of the axes of the hinges 36, 37 and 49.

75 75 Each plate 45, while being mounted for movement with its respective brace 35, may also move independently of its respective brace by virtue of its separate hinged connection to the frame 20. It will be noted, however, that each hinge

plate 45 slightly overlaps the end of its respective brace 35, and for the purpose of holding these overlapping portions of the plate and brace in juxtaposition to each other, there is fixed to each brace 35 a spring wire member 50. Each wire member has its one end anchored in its respective brace and is embraced intermediate its ends by a clip 51 secured to its respective brace. The free end of each wire 50 passes slidably through an ear 52 formed on the adjacent edge 10 of its respective hinge plate 45 so that each wire 50 tends to hold its respective plate 45 flat against the brace 35 with which this plate is associated.

15 From the above it will be obvious that each leg is braced in one direction by a member 32 or 15 35 rigid therewith. Each leg 31 is further braced against movement to collapsed position by a toggle brace comprising its plate 41 and the member 32 connected to an adjacent leg 30. Each leg 30 is braced against movement to collapsed 20 position by a toggle brace comprising its associated plates 45 and 48. These toggle braces will be successively moved into or out of bracing position upon movement of one of the legs to open or collapsed positions, thus providing for a sequential movement of the legs to open supporting 25 positions or to collapsed positions where they are disposed within flange 21 as shown in Fig. 8.

30 In operation, with the legs in open position in the manner illustrated in Fig. 6 of the drawings, 30 any one leg may be grasped, as for example, the leg 31 and this leg moved in a direction transverse to the axis of its respective brace if sufficient force is exerted on the same. This movement of the leg is permitted by virtue of the fact that 35 the toggle braces are not positively locked in bracing position because of the fact that the axes of the hinges 40 and 47 are slightly out of the plane of the axes of the other hinges of the toggle braces of which they form a part. The axes 40 of the hinges 40 and 47 are, however, sufficiently close to the plane of the axis of the other hinges of the braces to require considerable force to collapse the braces, and this collapsing is further resisted by the springs 50 which act directly on 45 plates 45 and indirectly on plates 41 by way of braces 32 to hold the several toggle braces in bracing position.

50 If, therefore, sufficient force is exerted on leg 31, for example, this leg may be moved in the direction illustrated in Fig. 8 of the drawings. By virtue of the fact that the brace 35 of this leg moves immediately with the same, the free end of this brace tends to break the toggle brace disposed between the end of this brace and the next 55 adjacent leg 30, starting a collapsing of this leg. Further, the hinged connection between leg 31 and the adjacent end of the adjacent brace 32 tends to move this brace to start a collapsing of the other leg 30 in a direction transverse to its 60 respective brace 32. Thus the toggle brace between this leg 30 and the adjacent end of the brace 35 of the next adjacent leg 31 is broken, and the spring 50 associated with this brace tends to urge this leg 31 to collapsed position. This 65 latter leg is also urged to collapsed position by virtue of the hinged movement of the brace 32 of the next adjacent leg 30 which is moved toward collapsed position by virtue of the breaking of its toggle connection by the brace 35 of the 70 first moved leg 31. Thus it will be apparent that a successive collapsing of the legs will be effected until the legs assume the position shown in Fig. 7 of the drawings. With the legs in collapsed position it will be apparent that they may be moved 75

to open position by a reversal of the above described actuation. Movement of one leg toward open position will effect a successive movement of the remaining legs to open position by virtue 5 of the toggle connections between the several legs.

If, in the collapsing of the legs, one of the legs 30 should be the one grasped and moved toward collapsed position, a slightly modified operation would result. Referring then again to Fig. 8, if 10 the leg 30 located at the lower left hand corner of the frame were moved toward collapsed position, the plate 45 associated with this leg would first move away from its respective brace 35, so that an immediate movement of the leg 31 associated 15 with this brace would not be effected. The brace 32, however, associated with the moved leg 30 would effect a breaking of the hinge connection between the free end of this brace and the next adjacent leg 31. This would start a 20 collapsing of this leg and the brace 35 of this leg would then start a breaking of the brace 45-43 between the end of this brace and the next adjacent leg 30 to start a collapsing of this leg. The brace 32 associated with this leg would in its 25 movement break the hinged connection between this brace and the last leg 31 to effect a collapsing of this leg. Thus should one of the legs 30 be first moved toward collapsed position, there 30 would be a complete successive breaking of the several toggle connections to effect a sequential collapsing of the legs.

The springs 50 act to maintain the plates 45 in the planes of the members 35. Thus these springs tend to hold the toggle braces formed by 35 the plates 45 and 48 in bracing position and, by thus tending to hold the legs 30 in open position, act indirectly through braces 32 to hold the toggle braces formed of these members and plates 41 in bracing position. Thus in moving the legs 40 to collapsed position, considerable force must initially be exerted on the legs to effect a breaking of the braces. If desired, recesses 53 may be made at desired points in the portion 24 of the frame 20 to receive the adjacent hinge plates 45 when the legs are in collapsed position.

If desired, the hinges 49 and 47 may be so arranged that their axes are in the planes of the toggle braces of which they form a part, with the result that the toggle braces would positively 50 lock the legs in open position. With the hinges arranged in this manner, the legs could be collapsed conveniently only by first directly breaking one of the toggle braces connected with a leg 30, the collapsing of this leg then effecting a sequential breaking of the remaining toggle braces in the manner previously described. If an attempt was made to collapse the legs by first moving one of the legs 31, it would be necessary to directly break the toggle brace associated with 55 this leg and the toggle brace associated with the next adjacent leg 30.

In Figs. 9 to 16, inclusive, a slightly modified form of construction is disclosed as comprising a table frame 20^a having a depending flange 21^a within which the legs of the table may be folded. The frame is provided with an upwardly extending flange 22^a within which the table top 23^a is mounted. In this form of construction the table top is preferably rigid with the frame 20^a, and the braces for the several legs are preferably 60 hingedly connected to the table top.

In this embodiment of the construction the legs are designated by the reference character 60, there being four of these legs, one being disposed at each corner of the table. Rigid with the

upper end of each leg is a brace 61, each brace extending from its respective leg toward the next adjacent leg in the series. Each brace is of flaring skirt shape in elevation and is of gradually decreasing cross sectional thickness from its respective leg to its free end. Each brace may be 5 hollow in structure, being formed of sheet metal plates 62 and 63 suitably secured together and ribbed for the purpose of reinforcement.

Fixed to the under face of the table top at each 10 corner is a right angled sheet metal plate member 65, each member preferably being provided with a boss 66 constituting a seat for the upper end of the leg associated with its respective corner. Each plate 65 is also preferably provided with 15 a border reinforcing flange 67, and formed in this flange are hinge eyes 68, 69, 70, 71, and 72.

Each brace 61 is hingedly connected at its one end to the hinge eyes 68 and 69 as by the hinge eyes 13 and a pintle 74. The free end of each 20 brace 61 is hingedly connected to the hinge eye 72 of the next adjacent plate 65 by a hinge eye 75 and a pintle 76. Thus the upper ends of the 25 braces are hingedly connected to the plates 65 which in turn are fixed to the under face of the 30 table top so that the legs may be moved to collapsed position.

Hingedly connected to the upper end of each leg 60 is a plate 80, and each of these plates is hingedly connected as by a hinge 81 to a plate 82, 30 the plates 80 and 82 being similar to the plates 48 and 45, respectively, previously described. The axis of the hinge 81 substantially bisects the angle between the adjacent braces 61, the planes of these adjacent braces intersecting each other adjacent the intermediate leg.

Each plate 82 is hingedly connected to its adjacent plate 65 by the hinge eyes 70 and 71 formed on this plate, there being suitable hinge pintles 40 provided for this purpose in the manner clearly illustrated in Fig. 12 of the drawings.

Each plate 82 slightly overlaps the adjacent end of its associated brace 61, and for resiliently holding each plate 82 in the plane of its associated brace, there is provided a spring member 85 mounted in the brace and having its one end 86 anchored in the brace adjacent the leg end thereof. The opposite end of each spring is angularly bent with reference to the body portion thereof and is anchored to the adjacent portion of the adjacent plate 82 with the result that any relative movement between the plate 82 and its respective brace is resisted by a twisting of the spring 85.

In this form of construction each leg is braced 55 in one direction by a member 61 rigid therewith. Each leg is further braced against collapsing by a toggle brace comprising plates 80-82. The hinges 81 of these braces are adapted to move to dead center position when the legs are fully 60 opened, or in the position shown in Fig. 10 of the drawings, the toggle braces thus being locked in open position so that the legs may not be collapsed by merely exerting a force on one of the legs tending to collapse the same. The plates 80 65 and 82 are limited in their outward movement by engagement of the overlapping portion of each plate 82 with its respective brace 61, while each spring 85 acts to hold its respective toggle brace in the locked position.

In operation and with the legs opened, it is necessary to directly break one of the toggle braces prior to collapsing of the legs. This is illustrated in Fig. 11 of the drawings wherein the 70 toggle brace designated by the reference charac- 75

ter A has been directly broken by the application of pressure on one of the plates 80 or 82. With this toggle brace broken, the leg 60 may be moved toward collapsed position and the member 61 associated with this leg will directly break the toggle brace associated with the next adjacent leg in the series. The member 61 connected with this leg will then break the toggle brace of the next adjacent leg, and this operation will be continued until all of the toggle braces have been successively broken. Thus movement of any one of the legs toward collapsed position will effect a sequential or successive movement of the remaining legs to collapsed position, the movement in this case being entirely successive because of the fact that no one of the legs may be collapsed prior to the direct breaking of its respective toggle brace.

In this case the springs 85 will at all times tend to maintain the plates 82 in the plane of their respective braces 61. Thus these springs will, when the legs are moved toward open positions, force the plates 82 outwardly to move the hinges 81 to the dead center position and to thus lock the toggle braces. Further, when the legs are in collapsed position, the springs 85 will tend to hold the braces 61 closely adjacent their respective plates 80 to thus aid in holding the legs collapsed.

From the above it will be apparent that the invention provides supporting legs for an article of furniture, these legs being arranged in series and so connected that movement of one leg to supporting or non-supporting position will effect a successive movement of the remaining legs to one of these positions. The structure will find particular utility when incorporated in a table construction, but may be adapted for use in connection with other articles of furniture.

While the invention has been described with some detail, it is to be understood that the description is for the purposes of illustration only and that the right is reserved to make such changes in the details of construction and arrangement of parts as will fall within the purview of the attached claims.

What I claim as my invention is:

1. In an article of furniture, a deck, a plurality of legs for said deck movable to supporting and non-supporting positions, and means operable upon movement of one of said legs to either of said positions to successively move the other legs to said position.

2. The combination with an article of furniture including supporting legs movable to supporting and non-supporting positions, of connections between said legs operating upon movement of one of said legs to either of said positions to effect a sequential movement of the remaining legs to said position.

3. The combination with an article of furniture including legs movable to open and collapsed positions, of a brace associated with each leg, each brace being movable to bracing and non-bracing positions, and means associated with each leg and adapted to be actuated solely thereby operable upon movement of said leg to open or collapsed position to move the brace of an adjacent leg to bracing or non-bracing position.

4. In combination, a frame, supporting legs for said frame movable to open and collapsed positions, and toggle braces associated with said legs operating upon movement of one of said legs to either of said positions to successively move the remaining legs to said position.

5. In combination, a frame, a plurality of legs for said frame movable to open and collapsed positions, and means connecting said legs in an endless series operating upon movement of one of said legs to either of said positions to effect a successive movement of the remaining legs to the said position.

6. In combination, a frame, a plurality of legs free from direct connection to said frame, a brace rigid with each leg, and a hinged connection between the longitudinal edge of each brace and said frame providing for collapsing of each leg in a direction transverse to the longitudinal axis of its respective brace.

7. In an article of furniture, a deck, supporting legs for said deck, a brace rigid with each leg, hinged connections between the longitudinal edge of said braces and said deck, and a collapsible brace for each leg.

8. In an article of furniture, a deck, a plurality of legs movable to open and collapsed positions for supporting said deck, a brace for each leg, each brace being movable to bracing and non-bracing positions, and a member rigid with each leg operable upon movement of its respective leg to open or collapsed position to move the brace of an adjacent leg to bracing or non-bracing position.

9. In an article of furniture, a deck, a plurality of legs arranged in series for supporting said deck, said legs being movable to open and collapsed positions, a brace rigid with each leg, hinged connections between the longitudinal edge of each brace and the deck, and toggle braces associated with said legs for holding the same in open position.

10. In an article of furniture, a deck, a plurality of legs for supporting said deck, each of said legs being free from direct connection to said deck, a brace rigid with the upper end of each leg, each brace having a longitudinal edge disposed adjacent the under face of said deck, hinged connections between each brace and said deck, and means disposed between the brace of each leg and a next adjacent leg operating upon movement of one of said legs to open or collapsed positions to move the other of said legs to the said positions.

11. In an article of furniture, a deck, a plurality of legs for supporting said deck, toggle braces for said legs, said toggle braces being adapted to be locked in extended position when said legs are in open position, and means operating upon the breaking of one of said toggle braces and the movement of one of the legs toward collapsed position to effect a successive breaking of the remaining toggle braces to provide for the successive movement of the remaining legs to collapsed position.

12. In combination, a table top, a plurality of hingedly mounted leg units, a bracing means for each unit, and means extending from each leg unit toward an adjacent leg unit and actuated solely by the leg unit from which it extends for moving the bracing means of the adjacent leg unit to bracing or non-bracing positions.

13. In combination, a table top, a plurality of legs for said top movable to open and collapsed positions, a collapsible brace for each leg, and means operable to successively collapse said braces upon movement of one of said legs from open to collapsed position.

14. In combination, a table top, legs for supporting said table top, said legs being movable to open and collapsed positions, a brace rigid

with the upper end of each leg, a plate constituting an extension of each brace, and a second plate hingedly connecting each first mentioned plate to an adjacent leg.

5 15. In combination, a table top, means including a pair of legs for supporting said top, a brace rigid with the upper end of one of said legs, a plate hingedly connected to the other of said legs, and a hinged connection between said plate and the free end of said brace.

10 16. In combination, a table top, means including a pair of legs for supporting said table top, a brace rigid with the upper end of one of said legs, said brace having an edge adjacent to the 15 under face of said top, a hinged connection between the said edge of said brace and said table top, a plate hingedly secured to the other leg, a second plate hingedly secured to said first mentioned plate, a hinged connection between said 20 second plate and the table top, and resilient means normally maintaining said second plate in the plane of said brace.

25 17. In combination, a table top, a plurality of legs for supporting said table top, a brace rigid with each leg, a plate hingedly connected to each leg, a second plate hingedly connected to each of the first mentioned plates, means hingedly connecting each of said second mentioned plates to the table top, and resilient means for maintaining each of said second mentioned plates in the 30 plane of one of said braces.

35 18. In combination, a table top, a plurality of legs for supporting said table top, a brace rigid with the upper end of each leg and extending toward an adjacent leg, means hingedly connecting each brace to the table top providing for collapsing of each leg in a direction transverse to its respective brace, a plate associated with each brace, each plate being hingedly connected to the 40 table top for movement with its respective brace, a second plate hingedly connecting each of said first mentioned plates to an adjacent leg, and means resiliently maintaining each of said first mentioned plates in the plane of its respective 45 brace.

45 19. In combination, a table top, a plurality of leg units for supporting said top, means hingedly mounting said leg units providing for movement of said leg units to open and collapsed positions, a bracing means for each leg unit for holding the same in open position, and means associated with each leg unit and extending toward an adjacent leg unit for movement with its respective leg unit, about an axis substantially concentric with the axis about which its respective leg unit moves, for moving the brace of the adjacent leg unit to bracing or non-bracing positions.

50 20. In combination, a table top, a plurality of leg units for supporting said top, means hingedly mounting said leg units providing for movement of said leg units to open and collapsed positions, a bracing means for each leg unit for holding the same in open position, and means associated with each leg unit for movement about an axis substantially concentric with the axis about which its respective leg unit moves, and extending toward an adjacent leg unit for moving the brace of the adjacent leg unit to bracing or non-bracing positions.

55 21. The combination with an article of furniture including legs movable to open and collapsed positions, of a brace associated with each leg, each brace being movable to bracing and non-bracing positions, means associated with each leg operable upon movement of said leg to open

and collapsed position to move the brace of an adjacent leg to bracing or non-bracing position, and connections between each brace and its associated leg operable upon movement of the brace to bracing or non-bracing positions to move its 5 respective leg to open or collapsed position.

22. In an article of furniture, a deck, a plurality of legs movable to open and collapsed positions for supporting said deck, a brace for each leg, each brace being movable to bracing and 10 non-bracing positions, a member rigid with each leg operable upon movement of its respective leg to open or collapsed position to move the brace of an adjacent leg to bracing or non-bracing position, and means operable upon movement of 15 each brace to bracing or non-bracing position to move its associated leg to open or collapsed position.

23. In combination, a table top, a plurality of hingedly mounted leg units, a bracing means for 20 each unit, means extending from each leg unit toward an adjacent leg unit and actuated solely by the leg unit from which it extends for moving the bracing means of the adjacent leg unit to bracing or non-bracing positions, and means operable upon movement of each bracing means to bracing or non-bracing positions to move its 25 respective leg unit to open or collapsed positions.

24. In combination, a table top, a plurality of legs for said table top movable to open and collapsed positions, a collapsible brace for each leg, means operable to successively collapse said braces upon movement of one of said legs from open to collapsed position, and means operable upon the collapsing of each brace to move its 30 respective leg to collapsed position.

25. In combination, a table top, a plurality of leg units for supporting said top, means hingedly mounting said leg units providing for movement of said leg units to open and collapsed positions, a bracing means for each leg unit for holding the same in open position, means associated with each leg unit and extending toward an adjacent leg unit for movement with its respective leg unit, about an axis substantially concentric with 45 the axis about which its respective leg unit moves, for moving the brace of the adjacent leg unit to bracing or non-bracing positions, and means operating upon movement of each brace to bracing or non-bracing positions to move its respective 50 leg unit to open or collapsed position.

26. In combination, a table top, a plurality of leg units for supporting said top, means hingedly mounting said leg units providing for movement of said leg units to open and collapsed positions, a bracing means for each leg unit for holding the same in open position, means associated with each leg unit for movement about the axis of movement of its respective leg unit, and extending toward an adjacent leg unit for 60 moving the brace of the adjacent leg unit to bracing or non-bracing positions, and a connection between each brace and its associated leg unit operable upon movement of the brace to bracing or non-bracing positions to move its 65 respective leg unit to open or collapsed position.

27. In an article of furniture, a deck, a series of legs for said deck movable to supporting and non-supporting positions, and actuating means for moving said legs to said positions, the actuating means for each leg including as a part thereof the next prior leg in the series.

28. The combination with an article of furniture including supporting legs movable to sup- 75

porting and non-supporting positions, of actuating connections between said legs and including said legs as a part of said connections operating upon movement of one of said legs to either 5 of said positions to effect a movement of the remaining legs to said position.

29. The combination with an article of furniture including supporting legs movable to supporting and non-supporting positions, of actuating means for said legs for moving the same 10 to said positions, said actuating means being so constructed and arranged that after movement of one leg the movement of each successive leg

is dependent upon the prior movement of an adjacent leg.

30. In a table, a table top, a plurality of cleats hinged to said top, a leg carried by each cleat, and a collapsible brace connecting each leg with the cleat of the next adjacent leg. 5

31. In combination, a top member, a plurality of cleats hinged to said top, a leg carried by each cleat, and means connecting each leg with the cleat of an adjacent leg and capable of transmitting movement from any leg to each of the other legs. 10
